UNITED STATES PATENT OFFICE.

JOHN McCLELLAND, OF PHILADELPHIA, PENNSYLVANIA.

COMBINED SPARK TIMER AND OIL PUMP.

1,414,823.

Specification of Letters Patent. Patented May 2, 1922.

Application filed July 7, 1920. Serial No. 394,457.

To all whom it may concern:

Be it known that I, JOHN McCLELLAND, a citizen of the United States, residing at Philadelphia, in the county of Philadelphia 5 and State of Pennsylvania, have invented certain new and useful Improvements in Combined Spark Timers and Oil Pumps, of which the following is a specification.

One object of my present invention is 10 to provide an improved device of the same general character as that disclosed in my United States Patent No. 1,344,953 of June 29, 1920, which will operate to successively cause ignition of the respective charges in 15 the cylinders of an internal combustion engine and at the same time will operate as a pump for supplying and circulating oil to any of the working parts of the engine or machine to which it is attached.

One of the main objects of my present invention is to provide simplified means for effecting the advance of the spark or ignition and at the same time not to interfere with the proper pumping of the oil.

A still further object is to provide an improved arrangement of the ignition and oil pumping brushes so as to increase or extend the life thereof and to make the device more easy to operate.

These objects, and other advantageous ends which will be described hereinafter, I attain in the following manner, reference being had to the accompanying drawings in which—

Figure 1 is an end elevation of my improved spark timer and oil pump,

Figure 2 is a section taken on the line 2—2 of Figure 1,

Figure 3 is a section taken on the line 40 3—3 of Figure 2,

Figure 4 is a section taken on the line 4—4 of Figure 2,

Figure 5 is a perspective view of an end or oil distributing cap which forms a part 45 of my invention,

Figure 6 is a section taken on the line 6—6 of Figure 2, and

Figure 7 is a fragmentary section taken on the line 7—7 of Figure 3.

Referring to the drawings, 8 represents 50 a supporting structure which for example may be a portion of the case of an internal combustion engine through which the cam shaft 9 extends. A cylindrical drum 10 is positioned so as to be free to oscillate be-

tween the supporting structure 8 and a fixed oil distributing cap 11; said drum having an axial extension 12 which provides a space 13 adjacent the outer surface of the end plate 14 of the drum 10. The end of the 60 cam shaft 9 is screw threaded and is provided with a collar 15 through the end of which a set screw 16 extends so as to abut the end of the cam shaft as clearly shown in Figure 2. The drum 10 is positioned 65 with its axis of oscillation eccentric to the axis of the cam shaft 9 and metallic contact plates 17 are arranged at spaced distances apart having their inner surfaces flush with the inner surface 18 of the drum 70 10 as clearly shown in Figure 3. These contact plates are insulated from the drum and have stems 19 extending outwardly through the drum provided with binding nuts 20 whereby the various ignition wires 75 may be attached in the usual manner. In the present instance there are four contact plates 20 illustrated such for example as for use in connection with a four-cylinder internal combustion engine and the wires 80 which are attached by the nuts 20 can be led to the respective spark plugs of the engine cylinder; it being noted that the cylinders are grounded in common connection with the drum and parts of the engine frame 85 in the usual manner of forming electro ignition connections of this type.

A brush carrier 21 in the form of a metallic disk or annulus has a central bore 22 through which the cam shaft 9 extends and 90 said cam shaft is keyed to said brush carrier so as to rotate said brush carrier during the operation of the engine. The brush carrier 21 is of small diameter compared to the internal diameter of the surface 18 of the drum 95 10 and is arranged eccentrically thereto as clearly shown in Figure 3. The brush carrier 21 has two slots 23 and 24 arranged parallel with each other at opposite sides of the bore 22. Brushes 25 and 26 are slidably mounted respectively in the slots 23 and 24 and have their outer ends movable in opposite directions by springs 27 so as to cause said outer ends of the brushes to contact with the inner surface 18 of the drum 105 and also with the inner surfaces of the contact plates 17 during rotation of the cam shaft and brush carrier. The brush 25 is preferably made of metal throughout its entire length while the brush 26 has its outer 110

- end provided with a tip 28 of material which is a non-conductor of electricity. Thus during the rotation of the cam shaft and brush carrier, the brush 25 will successively contact with the contact plates 17 to cause successive ignition or sparks within the respective cylinders of the engine and the drum has an arm 29 which may be connected with a rod 30 to oscillate the drum so as to advance or retard the spark by changing the relative position of the contacting plates 17 with respect to the brush 25. The brush 26 in the present instance performs no function with the ignition but co-acts with the brush 25 in causing a pumping or circulation of oil into and out of the space between the peripheral edge of the brush carrier 21 and the surface 18 of the drum in a manner herein-after described.
- 10 The extension 12 is secured to the drum by means of bolts 31 and the outer surface 32 of the extension 12 is ground plane to engage the inner ground plane surface 33 of the cap 11. The cap 11 and extension 12 are held in axial arrangement with each other by means of a cap screw 34 which passes freely through a hole 35 in the cap 11, and fits within a tapped hole 36 in the extension 12 as clearly shown in Figure 2.
- 15 A coiled spring 37 is interposed between the head of the cap screw and the inner surface of a recess 38 in said cap 11 so that the surfaces 32 and 33 of the extension 12 and cap 11 will be held in close engagement with each other but at the same time will permit an oscillating movement of the drum 10 and extension 12 relatively to the cap 11 and supporting structure 8.
- 20 The extension 12 has two ports 39 and 40 which lead inwardly from the surface 32 and communicate with extensions 41 and 42 of said ports within the drum 10; said extensions 41 and 42 of the ports 39 and 40 communicating with the interior of the drum 10 at points substantially diametrically opposite as clearly shown in Figure 3 so that said extensions 41 and 42 of the ports 39 and 40 will always be at opposite sides of each of the outer ends 25 and 26. These ports 25 communicate with the substantially crescent shape space 43 between the peripheral edge of the brush carrier 21 and the inner surface 18 of the drum. The cap 11 has two oil pipes 44 and 45 leading therein and the 30 passageways of these pipes communicate with slots 46 and 47 which lead to the surface 33 of said caps for registry with the ports 39 and 40 in the extension 12. The slots 46 and 47 are arranged concentrically to the axis of oscillation of the drum and extension 12 of said drum and these slots 46 and 47 are of such length as to permit oscillation of the drum 10 in either direction to the extent of the advancing and retarding 35 movement for the advance and retard of the
- sparking or ignition without possible chance of the slots 46 and 47 moving out of registry with the ports 39 and 40. The pipes 44 and 45 may lead to any part of the engine when it is desired to pump or circulate oil and 70 during the rotation of the cam shaft and brush carrier, the oil will be drawn in through the pipe 44 and forced out through the pipe 45.
- 75 By arranging the brushes 25 and 26 parallel as illustrated in Figure 3 they will present a comparatively wide end surface to the inner surface 18 of the drum and the inner surfaces of the contact plates 17 and thus a smooth and positive engagement may be 80 had between the brushes and the inner surface of the drum and contact plates.
- 85 While I have described my invention as taking a particular form, it will be understood that the various parts of my invention may be changed without departing from the spirit thereof, and hence I do not limit myself to the precise construction set forth, but consider that I am at liberty to make such changes and alterations as fairly come 90 within the scope of the appended claims.
- Having thus described my invention, what I claim as new and desire to secure by Letters Patent is:—
1. A device of the character described including an operating shaft; a drum pivoted independently of said shaft so as to be free to oscillate and having its axis of oscillation eccentric to the axis of rotation of said shaft; a brush carrier within said drum arranged eccentrically within the space of said drum; electric contact members spaced apart within said drum; and brushes carried by said carrier and adapted to successively contact with said members whereby at least one of said brushes will effect the closing of an electric circuit successively through said contact members, said drum having ports communicating with its inner space whereby said brushes during rotation of said carrier will draw fluid into said drum through one of said ports and force said fluid out through the other of said ports; substantially as described.
  2. A device of the character described including a drum having inlet and outlet ports communicating with the interior thereof; contacting members spaced apart within said drum; means within said drum adapted to electrically contact and complete a circuit through said members and also operative to draw fluid through one of said ports into the drum and force said fluid out of the drum through the other of said ports; and means for moving said drum so that the drum will oscillate relatively to said means whereby electric contact with said members may be advanced or retarded; substantially as described.
  3. A device of the character described in-

cluding an operating shaft; a drum free to oscillate and having its axis of oscillation eccentric to the axis of rotation of said shaft; a brush carrier within said drum 5 arranged eccentrically within the space of said drum; electric contact members spaced apart within said drum; brushes carried by said carrier and adapted to successively contact with said members whereby at least one 10 of said brushes will effect the closing of an electric circuit successively through said contact members, said drum having ports communicating with its inner space whereby said brushes during rotation of said carrier will draw fluid into said drum through one of said ports and force said fluid out through the other of said ports; a cap fixed 15 relatively to said drum; and pipes entering said cap, said cap including slots communicating with said pipes and adapted for registry with openings of said ports; substantially as described.

4. A device of the character described including an operating shaft; a drum; a brush carrier within said drum arranged eccentrically within the space of said drum and connected to said shaft; electric contact members spaced apart within said drum; and spring-pressed brushes carried by said 20 carrier and arranged parallel with each other at opposite sides of the axis of said carrier and adapted to successively contact with said members whereby at least one of said brushes will effect the closing of an 25 electric circuit successively through said contact members, said drum having ports communicating with its inner space whereby said brushes during rotation of said carrier will draw fluid into said drum through one 30 of said ports and force said fluid out

through the other of said ports; substantially as described.

5. A device of the character described including an operating shaft; a drum free to oscillate and having its axis of oscillation 45 eccentric to the axis of rotation of said shaft; a brush carrier within said drum arranged eccentrically within the space of said drum; electric contact members spaced apart within said drum; brushes carried by 50 said carrier and adapted to successively contact with said members whereby at least one of said brushes will effect the closing of an electric circuit successively through said contact members, said drum having ports 55 communicating with its inner space whereby said brushes during rotation of said carrier will draw fluid into said drum through one of said ports and force said fluid out through the other of said ports; an extension detachably secured to said drum and providing a space; a collar within said space detachably secured to said shaft and adapted to abut a part of said drum, said ports having portions leading through said extension and opening at the outer end surface thereof; a fixed cap having pipes leading therein and slots communicating with said pipes and leading to one surface thereof; and means for holding said surfaces of the 60 extension and cap together during the oscillating movement of said drum and extension; substantially as described.

In testimony whereof I have signed my name to this specification in the presence of 75 two subscribing witnesses.

JOHN McCLELLAND.
